UNITED STATES PATENT OFFICE.

HARRY M. PATCH AND RICHARD R. ROMNEY, OF SEATTLE, WASHINGTON, ASSIGNEES
TO ELLIS RESILIENT WHEEL CORPORATION, OF SEATTLE, WASHINGTON, A COR-
PORATION OF WASHINGTON.

RESILIENT WHEEL.

Application filed October 4, 1920. Serial No. 414,625.

To all whom it may concern:

Be it known that we, HARRY M. PATCH and RICHARD R. ROMNEY, citizens of the United States, residing at Seattle, in the county of King and State of Washington, have invented certain new and useful Improvements in Resilient Wheels, of which the following is a specification.

This invention relates to vehicle wheels 10 which are provided interiorly with a plurality of resilient bodies in lieu of inflated tires.

The object of our invention is to effect improvements in the construction of wheels of this character whereby the wheel structure is strengthened, and the resiliency increased with a more even distribution of the strains and stresses to which the wheel is subjected when travelling (and to enable the vehicle 20 to which the wheels are applied to be more easily propelled with greater comfort to the occupants).

These improvements consist principally in the peculiar construction and combination of 25 the wheel plate elements of the hub and rim members, and in the peculiar resilient connections between the respective plate elements.

The invention is illustrated in the accompanying drawings, in which—

Figure 1 is a side elevational view with part of an outer plate broken away; Fig. 2 is a sectional view taken through 2—2 of Fig. 1; Fig. 3 is a fragmentary transverse 35 sectional view of a portion of a wheel to illustrate a modification of the invention disclosed in the preceding views; and Fig. 4 is a side elevational view of one of the resilient bodies shown in Fig. 3.

In said drawings, 5 represents a rim of channel shape to receive the tire or tread 6 which is preferably of rubber. 7 represents a hub provided, as shown, with a peripheral flange 8 at one of its ends.

In Figs. 1 and 2, the rim 5 is mounted upon a felly 9 having centrally of its width a web 10 of annular shape with an inner diameter greater than the diameter of the hub 7. Said felly web is provided in its opposite 50 sides with a series of axial aligned cavities disposed in a circle concentric of the felly and of truncated conical forms to afford plane inner surfaces 11 and tapering peripheral surfaces 12.

Between the adjacent pairs of such cavities said web is provided with apertures 13 which are arranged to have their axes in the circle of the axes of the aforesaid cavities.

Between the felly 9 and said cavities said web is formed with a circumferentially arranged chamber 14 to provide two walls which are spaced apart to have their outer surfaces 16 in the planes of the outer edges of the respective cavity wall surfaces 12.

The felly web 10 extends into the space between two side plates 17 which with the hub 7 constitute a casing, said side plates being provided with sleeve elements 18 which are fitted upon the hub and to which the plates 17 are rigidly secured by bolts 19 engaging in holes provided in the hub flange 8.

The diameter of said casing is sufficient to extend radially of the wheel beyond said web cavities.

Provided upon each plate 17 interiorly of the casing is a series of cavities formed by the provision of circular ribs 20 as shown in Fig. 2. The cavities in the casing are furthermore arranged to face or be in opposed relations with the cavities in the sides of the web and, like such web cavities, have plane inner surfaces 21 and tapering peripheral surfaces 22.

Adjacent to the outer periphery of the plates 17, the same are provided with recessed portions 23 having tubular extensions 24 located to extend into the respective web apertures 13. 25 represent headed bolts passing through the tubular parts 24 to receive nuts 26.

These bolts and nuts serve supplementary to the bolts 19 to couple the plates together and render the casing rigid.

In practice, complementary parts 24 are of lengths to be brought into juxtaposition with each other when held by the respective bolts and serve to maintain the plates at a suitable distance apart. By providing recesses to accommodate the nuts 26 and heads of bolts 25 and by locating the plate cavities entirely within the casing we provide for the latter outer surfaces 27 having no protuberances.

Positioned within the spaces afforded by the complementary cavities of the web 10 and casing plates 17 are disk shaped bodies 28 of a resilient material, such as rubber.

Said disks are each of a thickness to normally extend between the respective cavity walls 11 and 21 and of a diameter to contact circumferentially with the respective 5 peripheral walls 12 and 22.

In order to accommodate the distortion of the disks when subjected to shearing stresses said disks are recessed in their opposite sides as indicated by 29 in Figs. 1 and 10 2, or they may be apertured as indicated by 29¹ with respect to the disks 28¹ illustrated in Figs. 3 and 4.

By such devices allowance is made for expansion and contraction of the material 15 composing the resilient bodies, and they enable the employment of disks instead of balls to accordingly occupy less transverse space with equal or greater quantity of material.

20 20 In the modification shown in Fig. 3, the various parts corresponding to those described with respect to Figs. 1 and 2 are denoted by primed (1) similar reference characters.

25 25 In such modification we employ four series of disks 28¹ instead of two series. To accommodate such additional disks two felly web elements 10¹ are used and also a partition plate element 17² which divides the interior of the casing, as shown.

The partition element 17² is provided at opposite sides with circular ribs 20² enclosing cavities for the reception of disks as shown.

30 35 The construction, operation and advantages of our invention will, it is thought be understood from the foregoing description.

What we claim is,—

1. In a vehicle wheel, alternating inner 40 and outer overlapping annular parts provided with opposing cavities, resilient circular plates provided in the respective cavities, and means extending through apertures provided in the inner of said parts for rigidly securing the outer parts together and affording movements thereto with respect to the inner of said parts.

2. In a vehicle wheel, the combination with a casing comprising two outer plates, 50 a hub rigidly secured to said plates, and a felly member having a web element interposed between said casing plates, said plates and web element being provided with opposing cavities, of means extending through 55 said web element and disposed adjacent to the outer peripheries of said plates for maintaining the latter at definite distances apart and resilient disks provided within the complementary cavities of the plate and 60 web member and bearing against the end

walls of said cavities and tending to maintain said member midway between the adjacent plates.

3. In a vehicle wheel, a felly having an inwardly directed web element, a hub, plates 65 extending outwardly from the hub, means for rigidly securing said plates to the hub said web and plates being provided with series of opposed cup shaped cavities, and circular rubber plates seated in the complementary cavities, and having their axes arranged parallel with the wheel axis.

4. In a vehicle wheel, a felly having an inwardly directed web element, a hub, plates 70 extending outwardly from the hub, means for rigidly securing said plates to the hub and in spaced relations with each other, said web and plates being provided with series of opposed cup shaped cavities, and circular rubber plates seated in the complementary 75 cavities, said rubber plates being formed with spaces to accommodate the material thereof when the rubber plates are distorted when subjected to shearing action.

5. In a vehicle wheel, the combination of 80 a felly having an apertured web element provided with a series of cavities in each side, a casing comprising the wheel hub and a circular plate disposed at each side of the felly web and rigidly secured to the hub, 85 said plates being provided with cavities facing the respective cavities of said web, bolts extending through the web apertures for coupling the plates, and circular plates of rubber seated within the laterally opposed 90 cavities of the web and the first named plates.

6. In a vehicle wheel, the combination of 95 a felly having an apertured web element provided with a series of cavities in each side, a casing having circular plates disposed at opposite sides of the felly web, said plate being provided with cavities facing the respective cavities of said web, plate spacing means provided within the web apertures, 100 bolts extending through the web apertures and cooperating with said spacing means for securing said plates against movements with respect to each other for coupling the plates, and rubber bodies seated within the 105 laterally opposed cavities of the web and plates.

Signed at Seattle, Washington, this 27th day of September 1920.

HARRY M. PATCH.
RICHARD R. ROMNEY.
